UNITED STATES PATENT OFFICE.

LOUIS P. SCHRAMM, OF TOLEDO, OHIO.

RAIL-SPLICE.

No. 892,313.

Specification of Letters Patent.

Patented June 30, 1908.

Application filed July 26, 1907. Serial No. 385,684.

To all whom it may concern:

Be it known that I, LOUIS P. SCHRAMM, a citizen of the United States, residing at Toledo, in the county of Lucas and State of Ohio, have invented new and useful Improvements in Rail-Splices, of which the following is a specification.

The invention relates to an improvement in rail splices, comprehending specifically a rail splice in which the coöperating parts are formed integral with the meeting ends of the rail, thereby insuring a firm connection and support.

The main object of the present invention is the production of a rail splice in which the rail ends are integrally formed to provide an interlocking connection adapted for assemblage by relatively endwise movement, each interlocking member including one-half the ball or tread of the rail, whereby a practically continuous tread is provided and the disadvantages of a transverse break at the meeting ends of the rails are avoided.

The invention will be described in the following specification, reference being had particularly to the accompanying drawings, in which:

Figure 1 is a perspective view showing two rail ends connected by my improved splice, Fig. 2 is a similar view showing the rail ends separated, Fig. 3 is a transverse vertical section through the connecting rails.

Referring to the drawings, it will be noted that the meeting ends of the respective rails are, in carrying out the present invention, complementary in structure, and, therefore, a detail description of one will suffice for both. In forming the interlocking member on the rail end the web of the rail is thickened on one side, as at 1, so that throughout the thickened portion the web of the rail is practically equal in thickness on one side to the thickness of the tread 2. In reducing the rail end to provide the splice member, the said end is cutaway longitudinally and centrally of the ball or tread 2, leaving a projecting tread portion 3 equal to one-half of the normal tread. The cutaway portion extends vertically through the web and flange, as shown, except that a series of longitudinally disposed ribs 4 are arranged in spaced relation on the web portion of the rail. These ribs extend in parallel relation from the rails proper beyond the cutaway portion, and are preferably three in number, though any number desired may be used.

The relatively forward end of the splicing member is reduced in height by the elimination of the ball or tread portion of the rail, thereby providing a tongue 5, which is approximately of a height equal to the distance between the base flange and ball of the opposing rail. The tongue 5, and the thickened web portion of the rail are formed with bolt openings 6, which may be of the usual elongated form to provide for contraction and expansion of the rail under extremes of temperature.

As hereinbefore stated it will be noted that the splice ends or members of the respective rails are duplicates in construction, except, of course, that the ribs 4 or one member are relatively offset from the ribs 4 of the other member, so that when said members are assembled, the ribs of one will fit between the ribs of the other.

In assembling the splice members to connect the rails, said members are joined by relatively longitudinal movement, the ribs 4 of one fitting between the ribs 4 of the other, and the tongues 5 of each member lying between the tread portion and base flange beyond the other member. Bolts 7 secure the parts in connected relation, as shown in Fig. 1.

In connected relation it will be noted that the joint, through the ball portion of the rail, is arranged in two spaced positions, one-half of the ball portion extending forwardly from each juncture. By this means vertical separation of the rail ends is impossible, and hence disadvantages of such separation are avoided. The ribs 4, in addition to guiding the rails into exact alinement, form an interlocking means which tends to maintain perfect alinement of the rail ends under all conditions. Furthermore, should the bolt fastenings of the rail ends become ineffective, the ribs and tongues would tend to maintain the necessary alinement of the rails, assuming the rails fastened beyond said ends by the usual spikes, and thereby prevent complete separation of the rails.

Having thus described the invention what is claimed as new, is:—

1. A splice for rail ends comprising interlocking members each including a thickened web portion and a tread portion centrally and longitudinally cut away throughout the length of the thickened web portion, said web portion being extended in advance of the tread terminal and reduced in width

throughout its height to provide a tongue projecting beyond the tread portion, that portion of the thickened web coextensive with the length of the reduced tread being reduced throughout its height and length and provided with a series of longitudinally disposed equally spliced ribs, the ribs of one rail end being aligned with the spaces between the ribs of the opposing rail end, whereby the reduced tread portions and the ribs on the respective rail ends interlock in assembling the parts and the tongues overlap the rail web beyond the thickened portion.

2. A splice for rail ends comprising interlocking members each formed with an offset web portion and having the tread overlying the offset web portion centrally and longitudinally cut away, the web portion beneath the reduced tread being of less thickness throughout its length and height than the reduced por-

tion of the tread, whereby the lower portion of the tread projects beyond the offset portion of the tread in the form of a shoulder, said offset portion being projected beyond the terminal of the reduced tread portion to provide a tongue, the offset portion of the web below the tread being formed with a series of spaced ribs arranged in parallel relation to the tread portion and coextensive in length therewith, the free side edges of said ribs projecting beyond the side edge of the tread, the ribs of one end being offset relative to the ribs of the remaining end to interfit said ribs in the assembling of the rail ends.

In testimony whereof I affix my signature in presence of two witnesses.

LOUIS P. SCHIRAMM.
